UNITED STATES PATENT OFFICE.

ADOLF ODKOLEK VON AUGEZD, OF BADEN, NEAR VIENNA, AUSTRIA-HUNGARY.

PARACHUTE.

1,081,137.

Specification of Letters Patent.

Patented Dec. 9, 1913.

Application filed July 31, 1912. Serial No. 712,435.

To all whom it may concern:

Be it known that I, ADOLF ODKOLEK VON AUGEZD, a subject of the Emperor of Austria-Hungary, residing at Baden, near Vienna, Empire of Austria-Hungary, have invented certain new and useful Improvements in Parachutes; and I do hereby declare the following to be a full, clear, and exact description of the invention, such as will enable others skilled in the art to which it appertains to make and use the same.

My invention relates to parachutes and has for its object a mechanism for efficiently and reliably opening parachutes attached to persons or objects above the ground. As experience shows most of the accidents with parachutes are due to the fact that the parachute does not fully open and therefore cannot carry the full load or is prevented from properly operating by the object itself which it is designed to carry. For avoiding these inconveniences and thereby rendering parachutes perfectly safe in use I provide according to my invention means for shooting the parachute as a whole upward by a driving agent such as an explosive charge or fluid under pressure and for shooting outward its ribs or periphery by driving agents such as explosive charges or fluid under pressure before the load to be carried by the parachute becomes operative upon the same. Thus my improved parachute becomes a reliable means for escape for aeronauts, for persons in burning houses and the like.

For compensating the recoil occurring on shooting the parachute I attach to the tube from which the parachute is shot a second tube extending in the opposite direction in which second tube an explosive charge is fired simultaneously with that serving for driving upward the parachute, the explosive charge in the second tube and the resistance to the expansion of the explosion gases of such charge being so determined that the two tubes are subject to equal and owing to the arrangement of the tubes opposite--recoil or reaction forces which compensate each other so that the two tubes as an entirety are not subject to any recoil. This is of particular importance when the device is used on aeroplanes or balloons.

The annexed drawings show by way of example one constructional form of a device embodying my invention.

Figure 1 is a central longitudinal section

of the same, Fig. 2 is a transverse section on the line A B, Fig. 1; Fig. 3 is a plan view of the head of the parachute rod and Fig. 4 illustrates the construction of the device when provided with a second tube for compensating for the recoil.

The shooting device for the parachute as a whole consists of a tube 1 similar in construction to the barrel of a fire arm and is secured to any desired part of the aeroplane, 60 balloon, building or the like in a vertical or inclined position by means of a standard 2. In the end of the barrel next to the standard there is provided a chamber 3 for receiving the driving agent preferably an explosive charge for instance gun powder. In this case the channel 4 leads from the chamber 3 to the bottom of the tube where a percussion primer 5 and a striker or firing pin 6 are arranged in any suitable manner. The 65 arm 7 of the striker is connected with a trigger cord 10 preferably by means of a metal eyelet 8 and is so shaped that the eyelet 8 engages a notch in the arm 7 normally closed by a plate spring 9 so that the eyelet cannot 70 slip accidentally from the arm 7. A sleeve 11 is adapted to slide along the tube 1 and to this sleeve that part of the device is secured which serves for driving outward the ribs or the periphery of the parachute that is to 75 say for opening or unfolding the same. This part consists of any suitable number of relatively short tubes 12 arranged radially. The inner ends of these tubes constitute 80 chambers for receiving the driving agent 90 such as explosive charges such chambers being connected by channels 14 with an annular channel 15 in a boss 16 to which the tubes 12 are secured. The boss 16 is fast on the sleeve 11. A firing mechanism of any suitable construction consisting for instance of a primer 17 and a striker 18 with a trigger cord 19 is secured to the boss 16 at some suitable place. The trigger cord 19 is considerably longer than the distance between 95 the striker 18 and the standard in the normal position of the former, the other end of the cord 19 being fastened to the standard. When the device is ready for use the central rod 20 of the parachute fits into the tube 1 100 as shown in Fig. 1 and carries at its upper end the head plate of the parachute such head plate fixedly secured to the rod and consisting of a rigid plate 21 provided with equidistant holes 23 serving for securing the 105

Figure 1 is a central longitudinal section

parachute cords 24 whereby when the parachute is unfolded the regularity of its shape is insured.

The fabric constituting the body of the parachute is secured to the plate 21, and the cords 24 are fastened to said body in the same manner as ribs are fastened in an umbrella. The cords carrying the load (not shown) are attached to the outer edge 10 of the fabric in any suitable manner.

15 The head plate of the parachute is provided with holes for the passage of air when the parachute falls together with the load for the purpose of preventing the parachute from tilting and its fabric from bursting. A number of cords 24 corresponding to the 20 number of tubes 12 extend below the body of the parachute and carry at their ends short plungers 25 which when the device is ready for use are in the tubes 12. In the 25 example shown in which the device is designed to be used on an aeroplane or on a balloon the standard 2 is secured to some part 26 of the frame and the trigger cord 10 is within the reach of the pilot. The 30 long ropes for carrying the load are suitably coiled or wound and fastened to a waist belt or the like carried by the pilot. The fabric of the parachute is folded around a frame work surrounding the device. The plungers 25 are in the tubes 12 and the rod 20 in the tube 1. The chambers 3 and 13 are charged with an explosive, the trigger cord 19 is fastened to the standard and the strikers 35 6 and 18 are in the position of rest shown in Fig. 1. The frame may be provided with a cover which may be readily removed or destroyed. Instead of the head plate 21 a larger disk 37 may be secured to the rod 20 as shown in dotted lines in Fig. 1 on 40 which the folded fabric of the parachute is placed and covered by a hood 38 of fabric or the like. The outer edge or periphery of the fabric is connected to the plungers 25 by cords 24 so that on shooting the 45 parachute and the plungers 25 the parachute is unfolded and opened, the hood 38 being thrown off. This unfolding is very regular owing to the fact that the fabric is regularly 50 folded on the disk 37.

According to Fig. 4 the tube 1 is connected with a similar tube 28 coaxial with it so that the open mouths of the two tubes are on opposite ends. For facilitating the arrangement of the igniting channels the two tubes are preferably separated by an intermediate block 29 in which the igniting channels 4, 30, 32 are provided. One of the channels say 30 leads outward to a primer 5 situated by a striker 6. The igniting channels 4 and 32 connect the channel 30 with the chambers in the tubes 1 and 28 respectively containing the explosive charges. Into the tube 1 the rod 20 of the parachute 65 is inserted and into the tube 28 a tightly

fitting plug 35 for instance of soft metal. The outer end of the tube 28 is conical resembling a choke bore barrel to such an extent that the plug 35 on being shot out from the tube 28 and owing to the choke bore of the latter meets with a resistance which is equal to the resistance offered by the parachute to its being shot out from the tube 1. Consequently the recoil due to the shooting of the parachute is equal to the recoil due 70 to the shooting of the plug 35 and owing to the arrangement of the tubes the recoils are in opposite directions and therefore the tubes 1 and 28 as an entirety and the structure in which they are mounted are not subject to 75 recoil at all. For preventing the plug 35 from leaving the tube 28 with too great a velocity this tube may be provided with a cylindrically bored extension, beyond its choke bore portion, such extension being 80 provided with lateral openings 36 for the escape of the explosion gases, when the plug has passed such openings. The pressure on the plug is thereby relieved so that it leaves the tube with a comparatively 85 small momentum or may be stopped in the part of the tube 28 extending beyond the openings 36 by simply closing the outer end of this tube. Instead of producing the resistance in the tube 28 by a choke bore and 90 a plug it may be produced by other means for instance by closing the mouth of the tube 28 by a disk of sufficient strength which is 95 torn by the explosion gases.

The operation of the device above described when used on an aeroplane or balloon is the following: In case of emergency the pilot pulls the firing cord 10 and thereby turns the striker 6 to such an extent that the eyelet 8 escapes from below the plate 9 whereby the striker is first cocked and then released and thus strikes against the primer 5 and fires the explosive charge in the tube 1 so that the folded parachute is driven upward and through the upward 100 pull of the cords 24 connected with the plungers 25 takes with it the sleeve 11 and the device for unfolding the parachute and stretching and tightening the firing cord 110 19. The latter cocks and releases the striker 115 18 whereby the explosive charges in the tubes 12 are fired at a moment when the parachute is so far above the aeroplane or balloon that it can unfold freely, the length of the cord 19 being suitably chosen 120 for this purpose. On firing the explosive charges in the tubes 12 the plungers 25 are shot radially outward causing the parachute to unfold properly by means of the cords 24. The sleeve 11 with its attached parts is 125 freed from the parachute upon the ejection of the plungers 25. The length of the cords carrying the load is so determined that it is only after unfolding the parachute that they are fully stretched so that the load to be 130

carried by the parachute is taken up by the same only after it has been properly unfolded and thus is securely supported by the parachute which then descends slowly together with the load.

10 Simultaneously with shooting the parachute the explosive charge in the tube 28 is fired and the plug 35 is driven out of the disk closing the mouth of this tube is torn whereby the recoil is compensated or deadened.

15 The device may also be used as a fire escape in buildings in which case the second tube 28 may be dispensed with. For this purpose the parachute may be mounted near a window in such a manner that it is shot obliquely upward for bringing it out of the reach of the flames. This oblique position of the parachute is also necessary when the 20 device is used on a biplane for avoiding the upper supporting surface. The length of the cords has to be determined according to the conditions in which the device has to be used. Any desired construction of 25 parachute may be used. The device may also serve for throwing up signal lights such as light balls, rockets or for firing projectiles from aeroplanes and balloons without subjecting the latter to recoil.

30 Claims:

1. The combination of a parachute, cords connected to the outer edge of the parachute, a plurality of tubes arranged substantially radial to the axis of the parachute, projectiles contained in said tubes and connected with the said cords, the said projectiles being adapted to be driven out by an explosive charge, and means for simultaneously firing the explosive charges in all of the radial 35 tubes.

2. The combination of a parachute, a shooting device for opening out the parachute comprising a set of tubes, substantial radial to the axis of the parachute and adapted to receive explosive charges, plungers in such tubes being adapted to be driven out by such shooting device, means for connecting such plungers with the edges of the 45 parachute, and means for simultaneously firing the explosive charges in all of the radial tubes.

50 3. The combination of a parachute, a shooting device for opening out the parachute comprising a set of tubes substantial radial to the axis of the parachute and adapted to receive explosive charges, plungers in such tubes being adapted to be driven out by such shooting device, means for connecting such plungers with the edges of the 55 parachute and means for simultaneously firing the explosive charges in all of the radial tubes, such latter means comprising a channel communicating with all the tubes of the shooting device and adapted to receive an 60 explosive charge, a firing mechanism for the 65 explosive charge in the said channel and means for actuating this firing mechanism.

4. The combination of a parachute, a shooting device for opening out the parachute comprising plungers being adapted to be driven out by such shooting device, means for connecting such plungers with the edges of the 70 parachute and means for shooting off the parachute from a stationary support, such means comprising a tube adapted to receive a driving charge, a sleeve adapted to slide along the said shooting off tube, the shooting device for opening out the 75 parachute being secured to such sleeve.

5. The combination of a parachute, a 80 shooting device for opening out the parachute comprising a set of tubes substantial radial to the axis of the parachute and adapted to receive explosive charges, plungers in such tubes being adapted to be driven 85 out by such shooting device, means for connecting such plungers with the edges of the parachute and means for simultaneously firing the explosive charges in all of the radial tubes, such latter means comprising a channel 90 communicating with all the tubes of the shooting device and adapted to receive an explosive charge, a firing mechanism for the explosive charge in the said channel, means for shooting off the parachute from a 95 stationary support, such means comprising a tube adapted to receive a driving charge, a sleeve adapted to slide along the said shooting off tube, the shooting device for opening out the 100 parachute being secured to such sleeve, a firing cord having attached one of its ends to the firing mechanism for the explosive charge in the communicating channel and its other end to the stationary support.

6. The combination of a parachute with a shooting device for opening out the parachute, means for shooting off the parachute, such means comprising a tube adapted to receive a driving charge, means for deadening the recoil of the shooting off tube, such latter means comprising a tube secured to and coaxial with the shooting off tube and adapted to receive a driving charge at its closed end next to the closed end of the 110 shooting off tube and means in the tube coaxial with the shooting off tube for offering a resistance to the escape of the driving charge at the other end of such tube.

7. The combination of a parachute with a shooting device for opening out the parachute, means for shooting off the parachute, such means comprising a tube adapted to receive a driving charge and means for deadening the recoil of the shooting off tube, the bore of such second tube tapering toward its outer end remotest from the shooting off tube, such second tube being adapted to receive a driving charge at its closed end next to the closed end of the shooting off tube and

a plug between such driving charge and its outer end.

8. The combination of a parachute with means for shooting the parachute upward, such means comprising a tube adapted to receive a driving charge, a sleeve adapted to slide along the said tube, radial tubes secured to such sleeve and adapted to receive explosive charges and plungers, cords connecting such plungers to the periphery of the parachute and means for simultaneously firing the explosive charges in the said radial tubes, substantially as and for the purpose described.
15. 9. The combination of a parachute with means for shooting the parachute upward, such means comprising a tube adapted to receive a driving charge, a sleeve adapted to slide along the said tube, radial tubes secured to such sleeve and adapted to receive explosive charges and plungers, cords connecting such plungers to the periphery of the parachute and means for simultaneously firing the explosive charges in the said radial tubes, such latter means comprising a firing cord having one of its ends attached to firing mechanism for the explosive charges of the radial tubes and its other end to an element rigidly connected to the first named tube.

10. The combination of a parachute with means for shooting the parachute upward, such means comprising a tube adapted to receive a driving charge, a sleeve adapted to slide along such tube, radial tubes secured to such sleeve and adapted to receive explosive charges and plungers, cords connecting such plungers to the periphery of the parachute and means for simultaneously firing the explosive charges in the said radial tubes, such latter means comprising a channel in the said sleeve communicating with all the radial tubes and adapted to receive an explosive charge, a firing cord having attached one of its ends to a firing mechanism for the explosive charge in the said channel and its other end to an element rigidly connected with the first named tube, substantially as and for the purpose described.
50. 11. The combination of a parachute with

means for shooting the parachute upward, such means comprising a tube adapted to receive a driving charge, means for automatically unfolding the parachute after shooting and means for deadening the recoil of the first named tube, such latter means comprising a tube secured to and coaxial with the first named tube and adapted to receive a driving charge at its closed end next to the closed end of the parachute shooting tube and means in the tube coaxial with the parachute shooting tube for offering a resistance to the escape of the driving charge at the other end of such tube, substantially as and for the purpose described.

12. The combination of a parachute with means for shooting the parachute upward, such means comprising a tube adapted to receive a driving charge, means for automatically unfolding the parachute after shooting and means for deadening the recoil of the first named tube, the bore of such second tube tapering toward its outer end remotest from the first named tube, such second tube being adapted to receive a driving charge at its closed end next to the closed end of the parachute shooting tube and a plug between such driving charge and its outer end, substantially as and for the purpose described.

13. The combination of a parachute, radial cylinders adapted to receive explosive charges, a plunger in each cylinder, a flexible connection between each plunger and the parachute, and means for simultaneously exploding the charges.

14. The combination of a support, a parachute, cylinders adapted to receive explosive charges, a plunger in each cylinder, a flexible connection between each plunger and the parachute, a striker for exploding the charge of the cylinders, and a flexible connection between each striker and the support.

In testimony whereof, I affix my signature, in presence of two witnesses.
